1 Claim. (Cl. 331—144)

The present invention relates to vertical sweep circuits for T.V. receivers and, more specifically, to temperature-compensated vertical sweep circuits.

It is common practice to utilize a multivibrator circuit for the production of the sawtooth currents necessary for vertical deflection of the electron beam in a television picture tube. As the ambient temperature of such a multivibrator increases during receiver warm-up, corresponding increases in resistance of various components of the circuit cause a decrease in magnitude of the sweep voltage and thus in picture size. The magnitude of the sweep voltage is decreased due to the lowering of the B+ by the increased resistance of the power transformer, filter choke and output transformer and also by the lowering of the efficiency of the output transformer and deflection windings. Thus, some form of temperature compensation is necessary to prevent objectionable picture shrinkage.

Prior art approaches towards providing such compensation have not proved entirely satisfactory. One such approach utilizes a low value thermistor connected in series with the vertical windings of the deflection yoke. As the ambient temperature rises, the thermistor resistance decreases, thereby increasing the efficiency of the output stage and compensating for picture shrinkage. However, such an approach has two basic disadvantages. First, such an approach is inefficient since substantial power is consumed by the thermistor. Further, such an approach is incompatible with present high efficiency yokes which necessitate the use of very low resistance value thermistors which are presently unavailable.

Another approach towards temperature compensation utilizes a thermistor in the plate circuit of the discharge tube to thereby change the plate load impedance or preferably the operating voltage of the tube to increase the amplitude of the sawtooth coupled to the grid of the driver tube as temperature increases. Although such an approach can provide reasonably good compensation, it has been found that certain sections of the circuit exert more effect on certain portions of the raster than on others. Therefore, the use of a single compensating element in this manner provides compensation at only one portion of the raster and does not provide compensation over the complete raster.

The above prior art disadvantages have been overcome by the temperature-compensated sweep circuit of the present invention.

Accordingly, an object of the present invention is to provide an improved temperature compensated vertical sweep circuit for a television receiver.

Another object is to provide a temperature-compensated vertical sweep circuit wherein complete compensation is achieved.

These and other objects are achieved in one embodiment of the invention by the provision of a multivibrator sweep circuit employing a thermistor and a temperature-dependent capacitance to effect temperature compensation. The thermistor is located in the bias circuit of the driver tube and serves to decrease the bias voltage at the grid of the tube as ambient temperature increases. The temperature-dependent capacitance is connected to the grid of the driver tube, the capacitance decreasing as ambient temperature increases to thereby develop an increased amplitude sawtooth wave at the grid of the driver

tube. Through the use of two temperature-sensitive elements in this manner complete compensation is achieved.

The novel and distinctive features of the invention are set forth in the appended claims. The invention itself 5 together with the further objects and advantages thereof may best be understood by reference to the following description and accompanying drawing, the single figure of which is a schematic representation of a preferred embodiment of the improved vertical sweep circuit of the present invention.

Referring to the drawing there is shown a multivibrator vertical sweep generator which is temperature compensated through the use of a thermistor and a temperature-dependent capacitance. The circuit comprises a sawtooth discharge generator tube V₁ having its cathode 1 grounded and its anode 2 connected to the boost supply through resistance R₁ and potentiometer R₂, resistance R₁ and potentiometer R₂ serving as load resistances for the discharge tube V₁. Further, the potentiometer R₂ serves as 10 a vertical linearity control.

The anode 2 of tube V₁ is connected through coupling capacitor C₁ to a pulse forming network comprised of temperature-dependent capacitance C₂, capacitor C₃ and resistance R₃. The pulse forming network is connected to 15 the grid of the driver tube V₂ and serves to develop a modified sawtooth wave at the grid 3. The tube V₂ is operated as a class A amplifier to reproduce the modified sawtooth at anode 4. The cathode 5 of discharge tube V₂ is grounded.

20 A feedback circuit is connected from the anode 4 of the driver tube V₂ to the grid 6 of the discharge generator tube V₁. The feedback circuit comprises serially-connected resistances and capacitances C₄, R₄, R₅, C₅ and potentiometer R₆ in conjunction with resistance R₇ and capacitance C₆ which are returned to ground from opposite 25 ends of resistance R₄. Circuit elements C₄ and R₇, in combination, serve as a differentiator to remove the low frequency components from the modified sawtooth wave present at the anode 4 of the driver tube V₂ so as to provide a feedback pulse of an optimum shape. Resistances R₄ and R₅, in addition to determining the amplitude of the feedback signal, serve in conjunction with capacitor C₆ to prevent undesired signals from the horizontal sweep circuitry from being coupled through the vertical deflection 30 coils to the grid 6 of discharge tube V₁. Capacitor C₅, in conjunction with potentiometer R₆, acts to define the free-running frequency of the multivibrator. The potentiometer R₆ serves as a vertical hold control which is varied to lock the multivibrator into synchronization with 35 pulses which are coupled from the vertical integrating circuit (not shown), to the anode 2 of tube V₁ or the grid 3 of tube V₂.

40 A biasing circuit is connected to the grid 3 of driver tube V₂. The biasing circuit comprises thermistor R₁₁, height control potentiometer R₈, resistance R₉, resistance R₁₀, and capacitance C₇. Thermistor R₁₁ and potentiometer R₈ are serially connected between the center tap of vertical hold potentiometer R₆ and ground. The tap of the height control potentiometer R₈ is connected through 45 resistances R₉ and R₁₀ to the grid 3 of driver tube V₂, the capacitance C₇ being utilized in connection with resistance R₉ as a filter to prevent coupling of the feedback signal from the grid 6 of tube V₁ to the grid 3 of tube V₂. The thermistor R₁₁ serves to decrease the bias on the grid 50 3 of tube V₂ when the ambient temperature increases to thereby increase the amplitude of the sawtooth appearing at the anode 4 of tube V₂.

55 A standard autotransformer 7, which serves to couple the multivibrator to the vertical deflection windings 8 and 9 of the deflection yoke, is connected in the plate circuit 60 of the driver tube V₂.

Although the operation of the conventional multivibrator circuit employed in this invention is well-known, a brief summary of such operation is given to allow a better understanding of the temperature compensation achieved by the present invention. As noted, the discharge tube V_1 serves as a sawtooth discharge generator. The operation can most easily be understood by assuming initially that plate current of the tube V_1 is cut off by a negative voltage at the grid 6. The negative voltage is developed by causing the grid 6 to draw grid current thereby charging the capacitors of the feedback network. The negative voltage thus stored on the capacitors of the feedback network slowly leaks off through the vertical hold potentiometer R_6 , height control potentiometer R_8 , and thermistor R_{11} to ground. During the time that the tube V_1 is cut off, capacitor C_2 and C_3 in the pulse forming network and coupling capacitor C_1 are charged in sawtooth fashion from the boost supply through vertical linearity potentiometer R_2 and load resistance R_1 . By the use of the pulse-shaping network comprised of capacitances C_2 and C_3 and resistance R_3 , a modified sawtooth is developed which is coupled to the grid 3 of tube V_2 . The modified sawtooth voltage wave form is necessary to assure linear deflection of the cathode ray beam.

After a prescribed period, the negative voltage on the grid 6 of the tube V_1 leaks off to ground to such a degree that tube V_1 conducts slightly. At that time, the capacitors C_2 and C_3 of the pulse-shaping network and coupling capacitor C_1 begin to discharge through the tube V_1 and an abrupt current change through the autotransformer 7 begins. The current change through the autotransformer 7 is in such a direction that a positive pulse appears at the anode 4 of tube V_2 . The positive pulse is coupled by the above-described feedback network to the grid 6 of tube V_1 so as to cause tube V_1 to become even more conductive. In this manner, a regenerative action is realized which results in a very rapid discharge of capacitors of the pulse-shaping network to complete the modified sawtooth wave form. When the pulse-shaping capacitors C_2 and C_3 are discharged, the positive pulse appearing at the plate 4 of the tube V_2 no longer exists and the grid current which is caused by the presence of the positive feedback pulse on the grid 6 of tube V_1 again allows the capacitors of the feedback circuit to charge so as to establish plate current cut off in the tube V_1 . Thus, the sawtooth cycle again commences. From the foregoing discussion, it is seen that the frequency of oscillation of the multivibrator is inherently a function of the time required for the negative cut-off voltage at the grid 6 of tube V_1 to leak off and allow conduction of the tube. This length of time is controlled by adjustment of the vertical hold potentiometer R_6 in such a manner that the free running frequency of the multivibrator is brought close to the frequency of the arriving synch pulses so that lockin between the multivibrator and the synch pulses is effected.

The vertical linearity of the circuit is controlled by varying potentiometer R_2 which, as a part of the plate load of tube V_1 , serves to define the rate at which the capacitors C_2 and C_3 charge to thereby control the sawtooth coupled to the grid 3 of tube V_2 . Height control is effected by varying potentiometer R_8 to change the bias and thus the operating point of the tube V_2 , the height control having a minimal effect on linearity since tube V_2 is always operated in its linear region as a class A amplifier.

In accordance with the present invention, temperature compensation of such a multivibrator sweep circuit is achieved by the action of thermistor R_{11} and temperature-dependent capacitance C_2 . As the resistance of thermistor R_{11} decreases with temperature, the bias voltage tapped from the height control potentiometer R_8 decreases, thereby decreasing the bias at the grid 3 of tube V_2 and causing an increased amplitude sawtooth wave to appear at the anode 4 of tube V_2 . In this manner, an increased amplitude sawtooth output is generated to maintain a constant

5

picture size. However, the use of R_{11} alone has been found to be insufficient to provide the desired complete compensation. In accordance with the present invention, perfect compensation is achieved by the use of the temperature-dependent capacitance C_2 in conjunction with the thermistor R_{11} . As the temperature of capacitor C_2 increases its capacitance value correspondingly decreases. Thus, the capacitors of the pulse forming network charge in a sawtooth fashion to a greater amplitude than exists at lower temperatures. The increased amplitude sawtooth at the grid 3 of tube V_2 results in an increased amplitude signal at the anode 4 to thereby further compensate for temperature increases.

Thus, it will be seen that as the ambient temperature of the multivibrator increases prior to the reaching of thermal equilibrium, the resistance of thermistor R_{11} and capacitance of capacitor C_2 decrease to provide compensation for the increased resistance of other components of the multivibrator. By the location of the compensating thermistor and capacitor in accordance with the present invention, complete temperature compensation can be achieved. Thus, the present invention is an improvement over prior art systems wherein complete compensation over the entire raster could not be achieved.

A sweep circuit compensated in accordance with the present invention has been found to be extremely stable over reasonably large temperature changes without the necessity of frequent adjustments of the various controls. At the same time, the circuit of the present invention is compatible with the use of high efficiency deflection yokes and serves to minimize power supply requirements by preventing the reduction of scan efficiency.

Although, by necessity, the specific circuit parameters vary in accordance with individual requirements, the following circuit values have been found to be completely satisfactory in one successful embodiment of the invention—

Thermistor: R_{11} , 105K.

Resistors: R_1 , 1.5 megohm; R_2 , 4 megohm; R_3 , 15K; R_4 , 68K; R_5 , 47K; R_6 , 1.8 megohm; R_8 , 500K; R_9 , 820K; R_{10} , 1 megohm.

Capacitors: C_1 , .018 microfarad; C_2 , .027 microfarad (temperature dependent); C_3 , 5,000 micro microfarad; C_4 , .018 microfarad; C_5 , .0039 microfarad; C_6 , 800 micro microfarad; C_7 , .033 microfarad.

Although the invention has been described with respect to certain specific embodiments, it will be appreciated that modifications and changes may be made by those skilled in the art without departing from the spirit of the invention. Therefore, it is intended by the appended claim to cover all such modifications and changes that fall within the true spirit and scope of the invention.

What is claimed as new and is desired to be secured by Letters Patent of the United States is:

A temperature-compensated multivibrator vertical sweep circuit for a television receiver comprising:

(a) first and second electron discharge devices, each discharge device having a control grid, cathode and plate,

(1) the plate of said first discharge device being coupled to the grid of said second discharge device,

(b) feedback means connected between the plate of said second discharge device and the grid of said first discharge device,

(c) pulse forming means connected between the anode of said first discharge device and a reference potential,

(1) said pulse forming means including capacitance means,

(d) said pulse-forming means being connected to the grid of said second discharge device to apply a signal thereto,

- (e) biasing means connected between the grid of said second discharge device and said reference potential,
(1) said biasing means including resistance means,
(f) said capacitance means and said resistance means exhibiting negative temperature coefficients of capacitance and resistance respectively to respectively increase the amplitude of the signal applied to said grid of said second discharge tube from said pulse forming means increases as temperature increases and to decrease the bias on said grid of said second discharge device as temperature increases.
